UNITED STATES PATENT OFFICE.

WILHELM LORENZ, OF CARLSRUHE, BADEN, GERMANY.

CARTRIDGE.

SPECIFICATION forming part of Letters Patent No. 331,511, dated December 1, 1885.

Application filed November 3, 1883. Serial No. 110,740. (No model.) Patented in Germany June 23, 1883, No. 26,549; in France August 6, 1883, No. 156,898; in Belgium October 13, 1883, No. 62,886; in England October 13, 1883, No. 4,872; in Italy October 13, 1883, No. 15,995; in Sweden December 13, 1883; in Austria-Hungary December 20, 1883, No. 33,2,533; in Denmark January 25, 1884, No. 2,274; in Spain March 29, 1884, No. 5,345, and in Norway September 23, 1884.

To all whom it may concern:

Be it known that I, WILHELM LORENZ, a subject of the Emperor of Germany, and residing at Carlsruhe, Grand Duchy of Baden, have invented certain new and useful Improvements in Cartridges, of which the following is a specification, the same being patented to me in Germany, No. 26,549, June 23, 1883; Belgium, No. 62,886, October 13, 1883; Great Britain, No. 4,872, October 13, 1883; Italy, No. 15,995, October 13, 1883; Sweden, December 13, 1883; Austria-Hungary, December 20, 1883; Denmark, No. 2,274, January 25, 1884; Spain, No. 5,345, March 29, 1884; Norway, September 23, 1884, and France, No. 156,898, August 6, 1883.

Figure 1 in the drawings is a section of the improved cartridge; Fig. 1^a, a detail section of the wad end. Fig. 1^b is a section showing a slight modification of the base of the cartridge. Figs. 1^c, 1^d are further detail sections of modifications; and Fig. 1^e, an enlarged section of the priming apparatus.

The said metal cartridges are composed of two parts, a case, *a*, and a base-piece, *b*, affixed as represented in Figs. 1 to 1^d. These parts comprise a base, *b*, having an outer annular lip, *d*^{*}, and an inner annular lip, *e*, the space between these lips being curved, as shown, and adapted to receive the edge of the body or case, which is the other part. The base has a projecting flange, *e*, which assists in extracting the shell after firing. The connection of these parts and their forms are so chosen that a self-acting packing is secured by pressing the cartridge-case against the base-piece, and a pressing of both these parts, but chiefly of the lip *d*^{*}, against the gun-chamber. The construction shows, nevertheless, means for an easy and quick extraction of the cartridge after firing. The form of the cartridge permits an easy introduction of the same into the chamber.

The drawings, Figs. 1 to 1^d, show several connections of case *a* with base *b* appropriate to the said requirements. In Fig. 1 the case is introduced into the interior of the base-piece and a little bent inward, the ring-formed nose *e* being afterward by hard pressure edged over

this bent part of the cartridge-case. Thus the gas-tight closing at this place, is made quite 50 secure, and will make superfluous any other joint by soldering, &c. Upon this the base-lip *d*^{*} is pressed closely to the sides of the cartridge-case. At the explosion of the powder the gases will press these joints yet more closely 55 together, while at the same time the whole cartridge-case, as above mentioned, is expanded. The base-rim of flange *e* serves as a hold for the extraction of the cartridge-case. The cartridge-case *a* and the base-piece *b* are 60 made separately by means of pressing and drawing.

In Fig. 1^b this cartridge-case is represented with the modification that the bending of the case into the border of the cartridge base is 65 made outward; but the making of both parts, their assembling together, and joining tightly are the same as above described.

In Figs. 1^c and 1^d the base-piece is arranged in the interior of the cartridge-case, an arrangement in which the lip *d*^{*} cannot so well 70 effect the gas-tight closing of the cartridge. In this modification the ring-formed nose *f* serves for connecting the bent border of the case with the base. This is also effected by 75 pressing the latter against the cartridge-case.

All these forms of metal cartridges after being filled with gunpowder, and having received a wad, *P*, are closed at the mouth of the case at *a'* by a cap, *m*, Fig. 1, or *m'*, Fig. 80 1^a, which may be of thin metal tightly soldered to the cartridge-case *a*. The cap-recess *e'* in the base of the cartridge is perfectly well closed by the percussion-cap, so no humidity can 85 reach the gunpowder.

The wad *P* of these cartridges is made of cork or other elastic material, with a wrapper, *p*, of felt or other suitable stuff saturated with grease, thereby the advantage is obtained that the greased wad moving through the barrel 90 cleans and greases the interior of the barrel at every shot.

The cartridge-cases *a* may be made of a solid and fire-resisting metal alloy or of tough steel. They should be made of rather thick sheets, 95 so that the cartridges employed for exercise

purposes may be used several times; or the material for these cartridges may be chosen from alloys that melt at a low temperature, and which, when worked in suitable thin sheets to cartridge-cases, will be destroyed and thrown out of the barrel at firing. In the latter case the closing tight the back of the cannon-chamber will be effected by the cartridge-base *b* or base-lip *d**, preferably made of steel. In this case the construction of the cartridge, or rather the cartridge-case, *a*, as represented in Fig. 1, is most suitable.

The interior surfaces of these cartridges are carefully tinned or covered with any other suitable material preventing the decomposition of the gunpowder in the charged cartridges during long storage, a decomposition otherwise inevitable by the presence of electric currents formed by the direct contact of the metal with the gunpowder.

The metal cartridge is provided with the common anvil or the cavity *e'*, as above described, with one or more touch-holes, *e''*, in which cavity the percussion-cap *f* (in this case provided with rim-fire) is placed. This cap has a coniform base, *j*, projecting inward, of which one side stands perpendicular to the direction of the explosion-bolt. The fulminate matter is placed in the ring *h'*, formed by the above-described conical base *j* and the bent-up rim of the cap. Thus the explosion-bolt will strike perpendicularly one point in the ring of detonating matter, and the ignition will be insured. The ring *j'* of the percussion cap presses against a corresponding conical excavation, *h'*, of the metal cartridge, forming thus a ring-shaped anvil.

I am aware that annular grooves have been formed in the base of a cartridge to receive the end of the cylinder, the base being swaged 40 down at the joint thus made by a mandrel.

I provide that the act of forcing the cylinder and base together shall sufficiently pack this joint for all necessary purposes of handling, &c., and that the explosion shall force the 45 joint closer.

What I claim is—

1. In a cartridge, the combination of the base *b*, having annular inclined groove, and lips *c* *d**, of different lengths, with the cylinder 50 *a*, the said cylinder and base being packed by the act of forcing them into proper contact, as set forth.

2. In a cartridge substantially as described, the combination of the cylinder *a* with the 55 wad *P*, of cork or similar flexible material, and the imperforate expanding-cap *m*, arranged between the wad and the projectile, as set forth.

3. The combination, with the cylinder and projectile, of the wad *P*, wrapped or otherwise 60 provided with an oiled covering, *p*, and the concavo-convex cap *m*, arranged between the wad and projectile, as and for the purposes set forth.

In testimony whereof I have hereunto set 65 my hand, at Berlin, this 24th day of August, 1883, in the presence of two subscribing witnesses.

WILHELM LORENZ.
